CLAIM

The ornamental design for a sticker, as shown and described.

DESCRIPTION

FIG. 1 is a perspective view of a sticker in accordance with one embodiment of the present invention; and

FIG. 2 is a front view of the sticker of FIG. 1; and,

FIG. 3 is a perspective view of a sticker in accordance with another embodiment of the present invention.

The stickers are intended for attachment to a protective helmet. The embodiments of the stickers shown in FIGS. 1 and 3 are mirror images of each other. The back or rear views of the stickers are not part of the claimed design.

1 Claim, 1 Drawing Sheet
